UNITED STATES PATENT OFFICE.

DONALD MACQUEEN, OF PORT HURON, MICHIGAN.

HOLDER FOR PLAYING-CARDS.

1,104,687.

Specification of Letters Patent.

Patented July 21, 1914.

Application filed February 11, 1914. Serial No. 818,073.

To all whom it may concern:

Be it known that I, DONALD MACQUEEN, a citizen of the United States, residing at Port Huron, in the county of St. Clair and 5 State of Michigan, have invented certain new and useful Improvements in Holders for Playing-Cards; and I do hereby declare the following to be a full, clear, and exact 10 description of the invention, such as will enable others skilled in the art to which it appertains to make and use the same.

This invention relates to new and useful 15 improvements in playing card holders, and has for its principal object to provide a device which is particularly adapted for use in playing the game known as Rhum poker.

Another object of this invention is to 20 provide a card holder from which cards may be drawn without any danger of the players seeing the cards or knowing the value thereof.

Still another object of this invention is to 25 provide a novel combination and arrangement of parts by means of which the above mentioned objects may be attained without the necessity of using any expensive apparatus.

A further object of the invention is to 30 provide a card holder in which the cards may be discarded without in any way exposing the value of the card to the players.

With the above and other objects in view, 35 the invention consists in the novel combination and arrangement of parts which will be fully set forth in the following specification and accompanying drawings, in which,

Figure 1 is a longitudinal sectional view 40 of a box constructed in accordance with this invention, Fig. 2 is a transverse sectional view of the same, Fig. 3 is a perspective view of the box, and Fig. 4 is an enlarged detail sectional view showing the hinge connection.

Referring now to the drawings by characters of reference, the numeral 1 designates 45 the bottom of the box which is preferably provided with a layer of felt or similar material 2 to prevent the same from scratching

50 the table or other article of furniture upon which it rests. Hingedly secured to the bottom are preferably provided the side walls 3 and 4 having formed centrally of their upper edges the recesses 5 and 6 respectively. A pair of end walls 7 and 8 are

hingedly secured to the bottom of the box as shown and are also provided with the depressions 9 and 10 respectively which co-operate with the depressions 5 and 6 in assisting the player to remove a card from 60 the top of the pack when the same is in place.

A false bottom 11 is placed in the box and spaced a short distance from the bottom thereof. Thus it will be seen that a closed 65 receptacle will be formed, the use of which will be described hereinafter. This false bottom is held in position by the supporting members 12, 13, 14, and 15 which co-operate with the bottom 1 and false bottom 11 70 to form a chamber for the reception of a suitable weight 16 which prevents the device from becoming accidentally displaced.

A suitable strip of elastic material is secured to each corner of the box as at 17 75 and is arranged to normally hold the sides and ends in the vertical position.

In the modified form of the invention which is illustrated in Fig. 4, instead of an ordinary hinge joint there are provided the 80 hinges 18 which connect the sides and ends to the bottom. Each of these hinges is arranged to force the free edges of the sides and ends toward each other and thus yieldably hold the same in such a way as to resemble a box like structure hereinbefore described. This construction is particularly adapted for the more expensive boxes and it is to be understood that the hinges used in the cheaper grade of box are preferably 85 those used in hingedly securing lids to paste board boxes of the ordinary character.

It will be apparent from the foregoing 90 that in use the box is placed in the desired position and a stack of cards placed therein. When it is desired to remove a card, it will be evident that the same may be withdrawn from the top of the pack without disturbing the balance of the cards and owing 95 to the fact that the side is flexible, the card need not be turned over until the same is in the player's hand, thereby eliminating any danger of the opponent seeing the card.

While in the foregoing there has been 100 shown and described the preferred embodiment of this invention, it is to be understood that such changes may be made in the combination and arrangement of parts as will fall within the spirit and scope of 105 the invention as claimed.

Having thus described my invention, I claim:

1. A device of the character described comprising a bottom, sides and ends hingedly secured to the bottom, a false bottom spaced from the bottom and forming a chamber, and a weight adapted to be placed in the false bottom to hold the device in the desired position.
- 10 2. A device of the character described comprising a bottom, a strip of felt secured to the bottom, ends and sides secured to the bottom, said ends and sides being provided with recesses in their free edges, means to normally hold the ends and sides in vertical position, and a weight adapted to be rested on the bottom of the box and adapted to hold the same from accidental displacement.

3. A device of the character described comprising a bottom, sides and ends hingedly secured to the bottom, a false bottom spaced from the bottom, walls holding the false bottom in spaced relation with the bottom, yieldable resilient means to normally hold the sides and ends in their vertical position, and a weight adapted to be inserted in the chamber formed between the bottom and the false bottom to prevent the box from becoming accidentally displaced.

In testimony whereof I affix my signature 30 in presence of two witnesses.

DONALD MACQUEEN.
